HINGE

Carl A. May, Akron, Ohio, assignor to The First
Central Trust Company, trustee, Akron, Ohio, a
corporation of Ohio

Application May 21, 1932. Serial No. 209,271

3 Claims. (Cl. 16—129)

This invention relates to hinges and refers more particularly to automobile door hinges which are adjustable.

Although automobiles have been developed to a high degree of refinement, the industry has not had available a satisfactory door hinge, the hinges now used being of the old hinge pin type that cannot be adjusted to compensate for inaccuracies in manufacturing automobile bodies, or for a sagging door, or a jammed door or body that often results when an automobile has been in a wreck.

The prior art hinges are expensive, are not provided with adequate means for lubrication, become worn and rattle from the vibration of the automobile, and they permit water, grit, and dirt to work into the bearing surfaces, which results in rapid wear and unsightly rust streaks on the body of the automobile below the hinge; and also, these prior art hinges require considerable force to swing the door, and when the door is swung, the hinge often squeaks from the results of the grit, rust, and lack of lubricating oil.

The general objects of the present invention are to obviate such faults and to reduce the cost of hinges. These objects are accomplished specifically by providing a hinge with a pair of hinge leaves having interfitting knuckles, said knuckles being so formed and proportioned as to permit limited relative movement of the leaves in all directions for purpose of adjustment of doors to their frames, serving to register the knuckles and to provide bearings therebetween at their adjacent surfaces, and adjustable screws connecting the balls with the knuckles, and guards to keep water, dirt, and grit away from the hinge wearing surfaces.

Of the accompanying drawings:

Fig. 1 is a perspective view of one form of the invention looking toward the outside of the hinge;

Fig. 2 is a similar view looking toward the inside of the hinge;

Fig. 3 is an enlarged cross-sectional view on line 3—3 of Fig. 2;

Fig. 4 is a view similar to Fig. 3, but showing a modified form of the invention.

Fig. 5 is a view similar to Fig. 3, but showing another modified form of the invention wherein the recesses in the end of the set-screws are non-concentric or off-center of said set-screws.

Fig. 6 is the same as Fig. 5 illustrating the tilting effect on the leaf of the hinge when one set-screw is given approximately a one quarter turn from the position shown in Fig. 5.

Fig. 7 is a view of the inner end of one of the set-screws; and

Fig. 8 is a view of the outer end of the other set screw per se.

5 Referring to Figs. 1, 2, and 3, it will be seen that the novel hinge there shown comprises a pair of relatively flat leaves 10 and 11 which are pivotally connected together, said leaves being provided with apertures 12 for accommodation 10 of bolts or screws whereby to be secured to the door and door frame respectively. The leaf 10 is integrally formed with a knuckle 14 which is adapted to be straddled by knuckles 15 and 16 of the leaf 11. The adjacent end portion of the 15 leaf 10 is curved to form skirts 17 which conceal the knuckles 15 and 16, and when the door is open, the ends of the skirts 17 are adapted to be abutted by shoulders 18 on the knuckles 15 and 16, thus limiting the opening movement. As 20 is clearly shown in Fig. 3, the space between the knuckles 15 and 16 is greater than the width of the knuckle 14, and as a result there is a certain amount of clearance between these respective parts. This clearance makes possible the adjustable connection between the knuckles as will 25 now be explained.

The upper and lower surfaces or ends of the knuckle 14 are formed with hemispherical recesses or sockets 20 and 21 for seating steel bearing balls 22 and 23 respectively. These balls 22 and 23 are held in their seats by correspondingly recessed ends of set-screws 24 and 25, which are 30 respectively screwed into aligned openings in the knuckles 15 and 16. By reason of the previously mentioned clearance between the knuckles, it will be evident that by axially adjusting the 35 leaves 10 and 11 may be varied to compensate for inaccuracies or inequalities in the door 40 mounting.

In order to maintain the working parts of the hinge in good condition, it is desirable that it be capable of lubrication. One way of accomplishing this is by providing the screw 24 with a small central bore 27 containing a cotton wick as shown in Fig. 3. Similarly the knuckle 14 has a hole 28 between the sockets 20 and 21, said hole 28 also containing a cotton wick. Suitable lubricant such as oil is used to substantially saturate the wicks, and periodically more lubricant may be added through the upper end of the set-screw 24; some of this lubricant will work its way past the ball 22 and through the hole 28 to the ball 55 23. Thus the bearing balls and their sockets are

prevented from corroding and kept in free-working condition.

It is desirable to prevent the set-screws 24 and 25 from turning after they have been adjusted to position, and various expedients may be resorted to for this purpose. In the illustrated embodiment of Fig. 3, this is accomplished by cap nuts 30 and 31 screwed on the ends of the screws 24 and 25 and engaging against the outer surfaces or ends of the knuckles 15 and 16. These cap nuts enhance the appearance of the hinge assembly in addition to locking the set-screws in place.

Several modified features of the invention are shown in Fig. 4. In the first place, the set-screw 24a has its inner end formed with a circular flange 35 adapted to surround a boss 26 on the upper side of the knuckle 14a. The inner end of the set-screw 25a has a reduced diameter 37 adapted to extend into a recess 38 in the lower side of the knuckle 14a. With this arrangement the bearing balls are raised above the planes between the knuckles, and dust and grit are prevented from entering the bearing ball seats. Secondly, the screws are shorter than in the first illustrated embodiments, and the cap nuts 39 and 40 have portions engaging in counter-bores 41 and 42 in the outer sides of knuckles 15a and 16a, with the result that the nuts do not project so far. The set-screws may have screw-driver slots or wrench sockets, as desired.

Several further modified features of the invention are shown in Figs. 5, 6, 7 and 8. In these views it will be seen that the hinge there shown comprises a pair of relatively flat leaves 10A and 11A which may be similar to those of Fig. 1. The leaves 10A and 11A are pivotally connected together, said leaves being provided with apertures for accommodation of bolts or screws whereby to be secured to the door and door frame respectively. The leaf 10A is integrally formed with a knuckle 14A which is adapted to be straddled by knuckles 15A and 16A of the leaf 11A. The adjacent end portion of the leaf 10A is curved to form skirts 17A which conceal the knuckles 15A and 16A, and when the door is open, the ends of the skirts 17A are adapted to be abutted by shoulders not shown but similar to shoulder 18 of Figs. 1 and 2, thus the opening movement of the door is limited. As is clearly shown in Fig. 6 the space between knuckles 15A and 16A is enough greater than the width of the knuckle 14A to provide ample clearance between these respective parts to permit a limited amount of tilting of 15A and 16A. This clearance makes possible the adjustable and tilting connection as will now be explained.

The upper and lower surfaces or ends of the knuckle 14A are formed with hemispherical recesses or sockets 20A and 21A for seating steel bearing balls 22A and 23A respectively. These balls 22A and 23A are held in their seats by correspondingly recessed ends of set-screws 24A and 25A, which are respectively screwed into aligned openings in the knuckles 15A and 16A. The recess or socket 50 in set-screw 25A is formed non-concentric with the circumference of said set-screw for the purpose of changing the alignment of the balls 22A and 23A. By means of the previously mentioned clearance between the knuckles, it will be evident that by axially adjusting the set-screw 25A by turning said set-screw that the recess 50 will progressively change its alignment with the recess 20A. It will also be evident that since the balls 22A and 23A are

the bearing in recesses 20A and 21A that as recess 50 is shifted that the direction of the axis of the hinge will change. Since one of the leaves of the hinge is fastened to the door jamb it will be seen that the change of angularity of the axis of the hinge will necessarily tilt the door according to the position to which the recess 50 has been turned. It will now be seen that when set-screw 24A also carries a non-concentric recess, that, with the vertical adjustment of the set-screws 24A and 25A substantial adjustment of the position of the door could be made in any desired direction by simply turning the adjustable screws. With the arrangement shown in Figs. 5 and 6 the knuckles 15A and 16A have been shortened to permit the cap nuts 52 and 53 to extend into the top and bottom edges of the hinge.

Although the invention has been described in connection with different preferred embodiments thereof, it will be apparent that different changes will suggest themselves to those skilled in the art without departing from the spirit of the invention which is limited, therefore, only by the prior art and the scope of the appended claims.

What I claim is:

23. 1. A hinge of the class described comprising a pair of hinge leaves having three interfitting knuckles, said knuckles being so formed and proportioned that the width of the inner knuckle is substantially less than the distance between outer knuckles and sufficient space is provided between the knuckles and the hinge leaves to provide clearance for limited relative movement of the leaves in the direction of the axis of the knuckles, and limited relative movement of the leaves in the transverse direction of the axis of the knuckles, the inner knuckle having its opposite edges formed with hemispherical bearing seats and a relatively small lubricating passage between said bearing seats, a pair of smooth surfaced balls disposed in said bearing seats and serving to register the knuckles, adjustment screws fitted in the outer knuckles and having their inner ends formed with hemispherical bearing seats for engagement with said balls, one of said bearing seats in said adjustment screws being formed non-concentric with said adjustment screw, said adjustment screws serving to snugly engage said balls in opposition to said bearing seats, and means for lubricating said balls.
30. 2. A hinge of the class described comprising a pair of hinge leaves having three interfitting knuckles, said knuckles being so formed and proportioned that the width of the inner knuckle is substantially less than the distance between the outer knuckles and sufficient space is provided between the knuckles and the hinge leaves to provide clearance for limited relative movement of the leaves in the direction of the axis of the knuckles, and limited relative movement of the leaves in the transverse direction of the axis of the knuckles, the inner knuckle having its opposite edges formed with hemispherical bearing seats, a pair of smooth surfaced balls disposed in said bearing seats and serving to register the knuckles, adjustment screws fitted in the outer knuckles and having their inner ends formed with hemispherical bearing seats for engagement with said balls, one of said bearing seats in said adjustment screws being formed non-concentric with said adjustment screw, said adjustment screws serving to snugly engage said balls in opposition to said bearing seats.
37. 3. A hinge of the class described comprising a pair of hinge leaves having three interfitting

knuckles, said knuckles being so formed and proportioned that the width of the inner knuckle is substantially less than the distance between the outer knuckles and sufficient space is provided between the knuckles and the hinge leaves to provide clearance for limited relative movement of the leaves in the direction of the axis of the knuckles, and limited relative movement of the leaves in the transverse direction of the axis of the knuckles, the inner knuckle having its opposite edges formed with hemispherical bearing seats and a relatively small lubricating passage

between said bearing seats, a pair of smooth surfaced balls disposed in said bearing seats and serving to register the knuckles, adjustment screws fitted in the outer knuckles and having their inner ends formed with hemispherical bearing seats for engagement with said balls, said bearing seats in said adjustment screws being formed non-concentric with said adjustment screws, said adjustment screws serving to snugly engage said balls in opposition to said bearing seats.
